TUNING MEANS

Robert G. Schrieber, Fort Wayne, Ind.

Application October 10, 1944, Serial No. 558,069

13 Claims. (Cl. 250—40)

(Granted under the act of March 3, 1883, as amended April 30, 1928; 370 O. G. 757)

1

This invention relates to the tuning of resonant circuits and more particularly to such circuits, adapted to be tuned through an unusually wide band of ultra high frequencies.

In the art to which this invention pertains it has been the custom to tune the resonant circuits through a limited band by means of a variable condenser and to alter the inductance of the circuit in steps to shift to an adjacent band. Alternatively, the value of the inductance has been varied continuously as by means of sliders. Each of these methods requires the use of leads, the lengths of which will vary from time to time.

However, in this art, it is necessary to decrease the length of the leads as much as possible in order to permit obtaining the low inductance necessary to get the ultra high frequency desired. Furthermore the radiation of the tuning circuits should be reduced as much as possible. It is therefore seen that the old methods do not operate to full advantage in that they require the use of undesirably long leads which will be too long to permit the higher frequencies being readily obtained.

Another disadvantage of the old methods is that unbalance of the L/C ratio gives less than optimum response to currents at the resonant frequency, as the tank circuit is tuned and the gain varies widely throughout the band of frequencies.

Furthermore, when the frequency of the oscillatory circuit is varied by means of the usual variable inductance, as to make large changes, the leads involved must of necessity be unbalanced for at least some part of the entire band, which will result in the undesired radiation of energy when operating in that particular part of the band.

Therefore, it is an object of this invention to provide a tuning device for an oscillatory circuit which will permit tuning over an unusually large frequency band.

It is an ancillary object of this invention to provide a tuning device of the type described which shall not necessitate the use of sliders, contacts or of tapped inductances.

Another object of this invention is the provision of a device which will permit tuning through the wide band and maintaining a constant L/C ratio.

Still another object of this invention is the provision of a tuning device which will permit substantially uniform gain while being tuned through a wide frequency band.

A still further object of this invention is to

provide a device of the type described which shall have symmetrical leads throughout its entire range and will have balanced currents and voltages at all times and will not produce undesired radiations.

2

Yet another object of this invention is to provide a circuit which shall have the shortest possible leads in order to produce oscillation of very short wavelengths.

10 In order to accomplish the object of this invention there is provided an inductance loop having a condenser stator connected directly to each end thereof. A single shaft is disposed in symmetrical relation to the inductance loop and to the two stators at right angles to the axis of the inductance. Mounted on the said shaft is a structure composed preferably of three or more metallic shading plates adapted to be rotated from a position parallel to the axis of the inductance to a position which is co-planar with the center of the inductance coil. Also mounted on the shaft is a condenser rotor having double plates, adapted to cooperate with each of the said stators.

15 20 25 The two stators are connected to the plate and grid respectively of a high frequency type tube such for instance as a "door knob" tube. The connection to the grid may be through a small condenser as will be described later. The mid-point portion of the inductance is connected to a high voltage source and through a condenser to ground. The rotor plates of the double variable condenser which has been described are adjusted relative to the shading plates so that when the inductance is at minimum value the rotor plates of each half of the double condenser will be out of the stators and the value of the condenser will be minimum.

30 35 40 Other objects and features of the present invention will appear more fully hereinafter upon consideration of the accompanying drawings which disclose one embodiment of the invention. It is expressly understood, however, that the drawings are designed for purposes of illustration only and not as a definition of the limits of the invention, reference for the latter purpose being had to the appended claims.

45 50 In the drawings, wherein similar reference characters denote similar elements throughout the several views:

Fig. 1 is a plan view of a tuning apparatus constructed in accordance with the principles of the present invention;

Fig. 2 is an elevation view of the apparatus shown in Fig. 1;

Fig. 3 is a circuit diagram of the tuning apparatus disclosed in Fig. 1; and

Fig. 4 is a circuit diagram of another high frequency circuit employing tuning means constructed in accordance with the present invention.

With reference more particularly to Fig. 1 of the drawings, a tuning device constructed in accordance with the principles of the present invention is disclosed therein including an inductor 10 shown in the form of an open, single metallic loop, constructed of bus bar material for example. The inductor 10 is supported in a horizontal plane by means of suitable insulators 11 mounted on a supporting base 12 which may comprise the bottom panel of the apparatus with which the tuning device is connected.

The tuning device further comprises a variable condenser 14 including a pair of multiplate stators 15 and 16, and a multi-plate rotor 17 adapted to cooperate with the stators 15 and 16 in varying degrees of capacitive relationship. The condenser stators 15 and 16 are respectively secured to the open ends of the inductor 10, and the rotor 17 is supported on one end of a shaft 18, positioned transversely of the inductor 10, to maintain the aforementioned relationship. The shaft 18 is rotatably mounted in the position disclosed by means of a bearing supporting member 19, located adjacent the condenser 14, and a journal is provided at the mid-point 20 of the inductor 10. The shaft 18 passes through the front panel 21 of the apparatus and a control knob 22 is positioned on the extended end thereof to provide a means for imparting rotation thereto.

An inductor tuning member 23 is mounted on the shaft 18 for rotation therewith to vary the inductance of the inductor 10. The inductor tuning member 23 is shown including a plurality of metallic shading plates 24 separated from each other by spaces 25 of insulating material. The tuning member 23 is of substantially circular configuration and is mounted for rotation within the inductor 10. With this arrangement, when the tuning member 23 is in the position depicted in Figs. 1 and 2 of the drawings, the inductor 10 is tuned to maximum inductance, whereas, when the shaft 18 is rotated so that the metallic shading plates 24 are in the plane of the inductor 10, a minimum value of inductance is offered.

As mentioned heretofore, it is an object of the present invention to provide a tuning device characterized in such a manner as to permit tuning throughout an unusually wide frequency band while maintaining a constant inductance to capacitance ratio. The foregoing is accomplished by the variable inductor-capacitor arrangement of Figs. 1 and 2, with the tuning member 23 and the rotor 17 mounted in predetermined relationship on the shaft 18. The relationship is such so that when the metallic shading plates 24 of the tuning member 23 are positioned relative to the inductor 10 to provide maximum inductance, the rotor 17 bears such capacitive coupling relation with the condenser stators 15 and 16 to provide maximum capacitance. With this arrangement, the ratio between inductive reactance and capacitance reactance is maintained substantially constant throughout the extremely wide frequency band of the tuning device.

In order to couple the tuning device to a useful circuit, to form an oscillatory circuit for ex-

ample, connection blocks 26 and 27 are respectively provided on the condenser stators 15 and 16. For a purpose that will appear more fully hereinafter, the connection block 27 is spaced from the condenser stator 16 by a strip of insulating material 28 to thereby form a capacitive coupling. In Fig. 1 the connection blocks 26 and 27 are shown respectively coupled to the anode 29 and to the control electrode 30 of an electron discharge device 31 which may be of the "door knob" type.

In Fig. 3 of the drawings the Fig. 1 device is disclosed in circuit form. A tuned circuit 32, including an inductance 33 and the capacitance between the stators 34-35, corresponds to the tuned circuit formed by the inductor 10 and the condenser 14 of Fig. 1. The stator 34 is connected to the control electrode 30 through a coupling capacitance 36, corresponding to the capacitance established by the strip of insulating material 28 of Fig. 1, and the stator 35 is directly connected to the anode 29. The capacitance between the stators 34-35 is varied by intermediate tuning element 37, and the value of the inductance 33 is determined by a short-circuited secondary 38 including an inductance 39 inductively coupled to the inductance 33. The tuning element 37 and the short-circuited secondary 38 respectively correspond to the rotor 17 and the inductor tuning member 23 of Fig. 1. As indicated in Fig. 3, the tuning element 37 and the short-circuited secondary 38 are ganged together to simultaneously vary the capacitance and the inductance of the tuned circuit 32. And it is expressly understood that the capacitance and inductance are varied in the predetermined relation described heretofore.

In Fig. 4 of the drawings the present invention is disclosed in connection with a conventional oscillator circuit of the Hartley type. This oscillator includes an electron discharge device 40 having an anode 41, a cathode 42 and a control electrode 43, coupled to a tuned circuit 44. The tuned circuit 44 includes a variable inductance 45 and a variable capacitance 46 constructed and simultaneously tuned in a manner described heretofore.

It will be seen from the foregoing that by the means provided not only may the characteristics of the oscillatory circuit be varied through extremely wide limits from the condition in which there is minimum inductance and minimum capacity to that in which there is maximum inductance and maximum capacity but that by a proper design of the various elements, the ratio between the inductive reactance and the capacitance reactance may be maintained substantially constant throughout this extremely wide frequency band. It will be appreciated that in this manner the inventor has accomplished the objects of his invention.

Although one embodiment of the present invention has been disclosed and described herein it is expressly understood that various changes and substitutions may be made therein without departing from the spirit of the invention as well understood by those skilled in the art. Reference therefore will be had to the appended claims for a definition of the limits of the invention.

The invention described herein may be manufactured and used by or for the Government of the United States of America for governmental purposes without the payment of any royalties thereon or therefor.

What is claimed is:

1. In a high frequency circuit, a pair of condenser stators, an inductance comprising a loop connecting said stators, a condenser rotor in capacitive relation with said stators, an inductance tuning means comprising a laminated rotor mounted within said loop, and means rotating said condenser rotor and said laminated rotor in such relative relationship so that when said laminated rotor is at right angles to the plane of said loop said condenser rotor is meshed with said stators, whereby there is provided a tank circuit having a very wide frequency range in which the ratio of inductive reactance to capacitive reactance is maintained substantially constant as the total circuit reactance is varied.

2. In a high frequency circuit, a pair of condenser stators, an inductance comprising a loop connecting said stators, a condenser rotor mounted for cooperation with both of said stators, an inductance tuning means including a short-circuited secondary mounted for rotation relative to said loop, and means simultaneously rotating said rotor and said short-circuited secondary in predetermined relation so that a tank circuit having a very wide frequency range is provided in which the ratio of inductive reactance to capacitive reactance is maintained substantially constant as the total circuit reactance is varied.

3. A high frequency tuning unit comprising a pair of condenser stators, an annular metallic band connecting said stators and forming parallel inductive paths, a first rotor in capacitive coupling relation to said stators, a second rotor in inductive coupling relation to said band and means moving said rotors in unison to simultaneously vary said coupling relations.

4. A high frequency tuning unit comprising a pair of condenser stators, an annular metallic band connecting said stators and forming parallel inductive paths, capacitance tuning means including a rotor in capacitive relation to said stators, inductance tuning means including a laminated rotor in inductive relation to said band and means moving said rotors in unison for varying the ratio of inductive reactance to capacitive reactance in a substantially constant manner.

5. A high frequency tuning unit comprising a pair of condenser stators, an inductance in the form of a loop connecting said stators, condenser tuning means capacitively coupled to said stators, inductance tuning means inductively coupled to said loop, and means simultaneously varying in predetermined relation the coupling between said condenser tuning means and said stators and between said inductive tuning means and said loop.

6. A high frequency circuit comprising a pair of condenser stators, an inductance in the form of a loop connecting said stators, condenser tuning means including a rotor mounted in variable capacitive coupling relation to said stators, inductance tuning means including a rotor mounted in variable inductive coupling relation to said loop, and means simultaneously rotating said rotors in predetermined relationship to vary the frequency of said circuit while maintaining the ratio of inductive reactance to capacitive reactance substantially constant.

7. A high frequency tuning unit comprising a pair of condenser stators, an inductance in the form of a loop connecting said stators, a rotatable shaft in a plane parallel to the plane of said loop and passing through said loop between said sta-

tors, a condenser tuning means mounted on said shaft in capacitive coupling relation to said stators, an inductance tuning means mounted on said shaft in inductive coupling relation with said loop, said condenser tuning means and said inductive tuning means relatively mounted on said shaft to provide maximum capacitive coupling relation when said inductance tuning means is in maximum inductive coupling relation to said loop, and means rotating said shaft to simultaneously vary said capacitive coupling relation and said inductive coupling relation.

8. In a high frequency circuit, a pair of condenser stators, an inductance comprising a loop connecting said stators, a rotatable shaft in a plane parallel to the plane of said loop and passing through said loop between said stators, a condenser rotor mounted on said shaft for cooperation with both of said stators, inductance tuning means including a short-circuited secondary mounted on said shaft in inductive coupling relation with said loop, said rotor and said short-circuited secondary mounted on said shaft in predetermined relation so that the ratio of inductive reactance to capacitive reactance is maintained substantially constant as the total circuit reactance is varied upon rotation of said shaft.

9. In a high frequency circuit, a pair of condenser stators, an inductance comprising a loop connecting said stators, a rotatable shaft in a plane parallel to the plane of said loop and passing through said loop between said stators, a condenser rotor mounted on said shaft for cooperation with both of said stators, inductance tuning means including a short-circuited secondary mounted on said shaft in inductive coupling relation with said loop, said rotor and said short-circuited secondary relatively mounted on said shaft so that the circuit is tuned to maximum inductance when said rotor cooperates with said stators to provide maximum capacitance, and means rotating said shaft.

10. A high frequency circuit comprising a pair of condenser stators, an inductance in the form of a loop connecting said stators, capacitance tuning means including a rotor mounted in variable capacitive coupling relation to said stators, inductance tuning means including a rotor mounted in variable inductive coupling relation to said loop, and means simultaneously varying said capacitive coupling relation and said inductive coupling relation to vary the frequency of said circuit while maintaining the ratio of inductive reactance to capacitive reactance substantially constant, the last named means including means for maintaining a predetermined relation between said rotors wherein the circuit is tuned to maximum capacitance when the inductance tuning means is in maximum inductive coupling relation with said loop.

11. In a high frequency circuit, a pair of condenser stators, an inductance comprising a loop connecting said stators, a rotatable shaft in plane parallel to the plane of said loop and passing through said loop between said stators, a condenser rotor mounted on said shaft in capacitive coupling relation with said stators, a laminated rotor mounted on said shaft in inductive coupling relation with said loop, said condenser rotor and said laminated rotor mounted in such relation on said shaft so that said laminated rotor is in maximum coupling relation to said loop when said condenser rotor is in maximum coupling relation to said stators, and means rotating said

shaft for simultaneously varying said capacitive and inductive coupling relations.

12. In a high frequency circuit, a pair of condenser stators, an inductance comprising a loop connecting said stators, a rotatable shaft in a plane parallel to the plane of said loop and passing through said loop between said stators, a condenser rotor carried by said shaft in capacitive coupling relation with said stators, tuning means comprising a plurality of metal plates mounted on shaft for varying the inductance of said loop in accordance with the angular position of said plates with respect to the plane of said loop, and means positioning said condenser rotor and said plates in predetermined relative positions on said shaft so that said plates are perpendicular to the plane of said loop when said condenser rotor is in equal capacitive coupling relation with said stators.

13. A high frequency tuning unit comprising a tuned circuit including a pair of condenser stators and an inductor connected across said stators, a condenser rotor associated with said stators for varying the capacitance thereof, a short-circuited inductor inductively coupled to said inductor for varying the inductance thereof, and means simultaneously varying the position of said condenser rotor with respect to said stators and the position of said short-circuited inductor with respect to said inductor.
